UNITED STATES PATENT OFFICE.

PERCIVAL TURNER HOUSTON, OF LONDON, ENGLAND.

SUCTION GAS-PRODUCER APPARATUS.

1,119,603.

Specification of Letters Patent.

Patented Dec. 1, 1914.

Application filed July 2, 1914. Serial No. 848,661.

To all whom it may concern:

Be it known that I, PERCIVAL TURNER HOUSTON, a subject of the King of Great Britain, residing in London, England, have 5 invented certain new and useful Improvements in Suction Gas-Producer Apparatus, of which the following is a specification.

This invention relates to suction gas producers in general but more especially for 10 those used in coöperation with gas engines for marine propulsion, and it consists in improved construction, and has for its objects:—(a) The elimination of hydrocarbon from the fuel and the utilization of the 15 combustion of the hydrocarbon vapors for the generation of steam. (b) The formation of coke for the production of producer gas free of hydrocarbon vapors for use for various purposes. (c) The generation and 20 supplying of steam for use in the gas producer and for auxiliary purposes while gas is being generated. (d) The prevention of adhesion of clinker and slag to the producer walls. (e) The use of the producer as an 25 ordinary steam generator for the supply of steam when gas is not required.

The invention will be considered as if it were applied to gas producing plant installed on a ship or vessel. With gas producers employed for marine purposes, it is 30 necessary that the producers should generate gas free from hydrocarbon vapors. It is also necessary that steam should be generated and supplied to the producer for the 35 enrichment of the gas by hydrogen. Steam also is required in a vessel or ship for a variety of auxiliary purposes such as heating, cooking and driving of auxiliary machinery, winches and other apparatus.

40 The invention will now be described with reference to the accompanying drawing in which—

Figure 1 is an elevation of a suction-gas producer constructed according to this invention, and Fig. 2 is a vertical section of the producer in Fig. 1.

The improved producer apparatus partakes 50 of the form of a combined gas producer and boiler, in which the producer furnace *a* is water-jacketed as at *b* and extended vertically forming an upper chamber *c* where the coking of the coal or other fuel takes place. In the top portion of the upper chamber is a combustion space or chamber 55 *c'*, from the crown *e* of which tubes *f* may pass vertically through the water and steam

space *g* to the smoke box *h* and smokestack *h'* in a similar manner to that found in known steam vertical boilers. The fuel for the furnace may be fed through a fire door *i* placed in the vicinity of the combustion space. Air is admitted through a conduit or belt *j* and one or more rings of tubes or nozzles *k* placed preferably just below the working level *l* of the fuel when the plant is 60 being used for the production of gas and generation of steam. Additional air as may be required for the combustion of the hydrocarbon vapors and other gases can be supplied through regulating shutters *m* on 65 the furnace doors *i* or in other suitable ways. The top of the lower or producer furnace *a* is preferably conical in shape as at *a'*, while a skirt plate *d* suspended within the conical portion forms with the latter an annular 70 space *a''* from which the gas can be drawn by means of tubes *n* passing through the water-jacket *b* into a gas bell or receiver *o*. 75

The gas-producer boiler may be mounted on a metal or other base *p* which can be provided with a removable step fire grate *q* and with doors *r* provided for the removal of ashes, etc.

Air for the producer is admitted through a suitable inlet or inlets *s* in the base, by 80 means of pipe *u*, the supply being controlled by a slide *u'* or other suitable device. Steam can be admitted by means of pipe *v*, in 85 valved communication with the steam space *g* and discharging into pipe *u*. Pipe *v* is 90 fitted with a regulating valve or cock *v'*. Suitable baffle plates or other means, not shown, are provided in the gas belt near the outlet so as to insure even suction over the area of the fire.

95 Poking holes *t* to the lower furnace or gas producing portion *a* should be provided through a number of the tubes *n* in the gas belt; similar provision for poking is made through the air tubes *k* to the upper furnace *c*. The apparatus is provided with 100 cleaning holes, man-holes and usual boiler mountings.

The coal or other fuel is fed through the furnace door *i* and is roasted or coked, the 105 hydrocarbon vapors being driven off and burned in the combustion chamber on mixing with the air introduced. The flames of these gases pass through the tubes *f* to the smoke box *h* generating steam in the surrounding water. The fuel as coke free 110 from hydrocarbons, reaches the lower fur-

nace *a* where gas is formed by the air and steam being drawn through the fire.

The quantity of steam generated by the combustion of the hydrocarbon vapors, with or without a certain quantity of producer gas drawn from the lower part of the producer, will be sufficient to supply steam for the gas making and for the various steam auxiliary engines or apparatus correlated with the producer. The provision of the water jacketing to the producer furnace prevents the adhesion of the clinker to the sides of the walls of same.

By fitting an induced draft to the up-takes from the boiler portion of the producer, the whole of the producer can be drawn up to a state of gas making in readiness for the supply of gas to the main engines. By lowering the fuel level to a position comparatively close to the top of the grate *q* for instance to the level *l'*, the apparatus may be used simply as a boiler for supplying steam, which, in the case of a vessel in port for loading or discharging purposes, can be utilized in working winches and other apparatus.

The gas producer boiler may alternatively be arranged with either horizontal or inclined smoke tubes, return smoke tubes, vertical, horizontal or inclined water-tubes, or tubes of the Galloway type placed in the upper furnace.

Having now described the nature of my said invention and the best means I know of carrying the same into practical effect, I claim:—

1. A combined suction gas producer and steam boiler apparatus comprising a producer furnace, a coking chamber embodying a combustion space, said chamber arranged in superposition in respect to and in open communication with the furnace, a second or outer chamber inclosing the furnace and the coking chamber and having a water and a steam space, a smoke box disposed above the said outer chamber and communicating with a flue or uptake, a series of tubes communicating with the combustion space of the coking chamber and the smoke box, means for drawing off gas from the producer furnace, means for admitting steam from the steam space in the outer chamber to the furnace, means for admitting air to the furnace and means for admitting air to the coking chamber.

2. A combined suction gas producer and steam boiler apparatus comprising a producer furnace, a coking chamber embodying a combustion space, said chamber arranged in superposition in respect to and in open

communication with the furnace, a second or outer chamber inclosing the furnace and the coking chamber and having a water and a steam space, a smoke box disposed above the said outer chamber and communicating with a flue or uptake, a series of tubes communicating with the combustion space of the coking chamber and the smoke box, means for drawing off gas from the producer furnace, adjustable means for admitting steam from the steam space in the outer chamber and air to the furnace, and means for admitting air to the coking chamber.

3. A combined suction gas producer and steam boiler apparatus comprising a producer furnace, a coking chamber embodying a combustion space, said chamber arranged in superposition in respect to and in open communication with the furnace, a second or outer chamber inclosing the furnace and the coking chamber and having a water and a steam space, a smoke box disposed above the said outer chamber and communicating with a flue or uptake, a series of tubes communicating with the combustion space of the coking chamber and the smoke box, means for drawing off gas from the producer furnace, means for admitting steam from the steam space in the outer chamber and air to the furnace, means for admitting air to the coking chamber, and adjustable means for admitting air to the said combustion space.

4. A combined suction gas producer and steam boiler apparatus comprising a producer furnace, a coking chamber embodying a combustion space, said chamber arranged in superposition in respect to and in open communication with the furnace, a second or outer chamber inclosing the furnace and the coking chamber and having a water and a steam space, a smoke box disposed above the said outer chamber and communicating with a flue or uptake, a series of tubes communicating with the combustion space of the coking chamber and the smoke box, means for drawing off gas from the producer furnace, adjustable means for admitting steam from the steam space in the outer chamber and air to the furnace, means for admitting air to the coking chamber and adjustable means for admitting air to the said combustion space.

In testimony whereof I have signed my name to this specification in the presence of two subscribing witnesses.

PERCIVAL TURNER HOUSTON.
